[57] **CLAIM**

The ornamental design for a pusher plate attachment for hand truck, as shown and described.

DESCRIPTION

FIG. 1 is a front and top perspective view of a pusher plate attachment for hand truck showing my new design, the broken lines are for illustrative purposes only and form no part of the claimed design;

FIG. 2 is a top plan view thereof;

FIG. 3 is a bottom plan view thereof;

FIG. 4 is a front elevational view thereof;

FIG. 5 is a rear elevational view thereof; and

FIG. 6 is a left side elevational view thereof, the right side view being a mirror image of that shown.

Fig. 1.

Fig. 2.

Fig. 3.

Fig. 4.

Fig. 5.

Fig. 6.
